(57) **CLAIM**

The ornamental design for a freestanding screen, as shown and described.

DESCRIPTION

FIG. 1 is a top perspective view of a freestanding screen showing our design;

FIG. 2 is a right end view of FIG. 1;

FIG. 3 is a front view of FIG. 1;

FIG. 4 is a left end view of FIG. 1;

FIG. 5 is a top view of FIG. 1; and

FIG. 6 is a bottom view of FIG. 1.

FIG. 7 is a top perspective view of a second embodiment of FIG. 1;

FIG. 8 is a right end view of FIG. 7;

FIG. 9 is a front view of FIG. 7;

FIG. 10 is a left end view of FIG. 7;

FIG. 11 is a top view of FIG. 7; and

FIG. 12 is a bottom view of FIG. 7.

FIG. 13 is a top perspective view of a third embodiment of FIG. 1;

FIG. 14 is a right end view of FIG. 13;

FIG. 15 is a front view of FIG. 13;

FIG. 16 is a left end view of FIG. 13;

FIG. 17 is a top view of FIG. 13; and

FIG. 18 is a bottom view of FIG. 13.

FIG. 19 is a top perspective view of a fourth embodiment of FIG. 1;

FIG. 20 is a right end view of FIG. 19;

FIG. 21 is a front view of FIG. 19;

FIG. 22 is a left end view of FIG. 19;

FIG. 23 is a top view of FIG. 19; and,

FIG. 24 is a bottom view of FIG. 19.

The diagonal shading lines in FIGS. 7-12 and 19-24 show the translucent nature of the covering of the present screens.
